UNITED STATES PATENT OFFICE.

GEORGE A. STEINER, OF SALT LAKE CITY, UTAH, ASSIGNOR TO AMERICAN LINEN SUPPLY CO., OF SALT LAKE CITY, UTAH, A CORPORATION.

TOWEL-CABINET.

1,287,787.

Specification of Letters Patent. Patented Dec. 17, 1918.

Application filed March 18, 1918. Serial No. 223,211.

To all whom it may concern:

Be it known that I, GEORGE A. STEINER, a citizen of the United States, resident of Salt Lake City, county of Salt Lake, State 5 of Utah, have invented certain new and useful Improvements in Towel-Cabinets, of which the following is a specification.

The object of my invention is to provide a towel cabinet and a means for holding a 10 bundle of towels therein which will allow the full wiping surface of the towel to be used conveniently and the soiled towel, when released, received in a suitable receptacle in the lower part of the cabinet.

15 A further object is to provide a holder in connection with a cabinet of this kind which will allow the clean towels to be grouped together in a bundle at the laundry, secured by a suitable holding means, carried to the 20 cabinet and placed therein and held together until the last towel has been used. Then the soiled bundle may be removed from the cabinet and a clean lot substituted therefor. The end to be attained, besides the convenience 25 in handling the towels, when grouped in a bundle, is, of course, to prevent as far as possible the loss of towels through pilfering.

The invention consists generally in various constructions and combinations, all as 30 hereinafter described and particularly pointed out in the claims.

In the accompanying drawings forming part of this specification,

Figure 1 is a perspective view of a towel 35 cabinet with my invention applied thereto,

Fig. 2 is a detail view, showing the tapes on the towels and the means for stringing them together to prevent separation and loss of the towels,

40 Fig. 3 is a modified construction, in which the tapes are provided with shorter loops to receive the securing means.

Fig. 4 is a detail view, showing one of the 45 tapes with a comparatively short loop thereon.

In the drawing, 2 represents a suitable cabinet, having a shelf 3 in the upper part thereof whereon the bundle of towels is placed. The walls of the cabinet extend 50 a considerable distance above this shelf and permit the placing of a considerable number of towels, laid out flat one upon another thereon. In this form the clean towels are brought from the laundry and placed upon 55 the shelf preparatory for use.

At the forward edge of the shelf I prefer to provide an upright ledge 4 which serves to hold the towels in place on the shelf, an opening 5 being formed between the end of this ledge and the adjacent upright wall of 60 the cabinet. The towels 6, when placed upon the shelf, have one corner opposite and near the opening 5 and this corner is provided with a comparatively long loop 7, made preferably of a suitable size of tape secured at its ends to the corner of the towel and extending out a suitable distance therefrom. The corner of the shelf 3 is preferably provided with a recess 8 and when the towels are placed on the shelf the bunch or 70 bundle of tapes at the corners thereof will hang down through the recess 8 into the space below the shelf in the cabinet and into this space, which I may designate as the soiled towel receptacle 9, the towels are 75 dropped after being used. 10 is a means, such as a wire or rod of suitable gage made preferably in the form of a ring, which at the laundry is threaded through the loops 7 of a suitable number of towels and the ends 80 of the ring or stringer are joined and secured together by a locking device, such as a seal 11. This work is all done at the laundry before the towels are taken out. Upon reaching the cabinet, the bundle of towels 85 is laid flat upon the shelf, with the loops 7 hanging down through the recess 8 beneath the shelf. The loops are of sufficient length so that each towel may be lifted from the pile and held in a convenient position in 90 front of the cabinet for use and then dropped into the soiled towel receptacle in the bottom of the cabinet. When the first towels are used, the weight of the bundle on the shelf will be sufficient to support several 95 towels hanging on the loops in the receptacle beneath and as the towels accumulate in this receptacle and it becomes partially filled with them, the pull on the loops will be relieved and the towels may be used one at 100 a time to the bottom without danger of the weight of the soiled towels pulling the clean ones off the shelf. When the last clean towel has been used the shelf will be clear and ready for a clean bundle, while those in 105 the receptacle beneath will be strung together, ready to be returned to the laundry.

In Figs. 3 and 4 I have shown a slight modification, which consists in providing a tape 12 with a comparatively short loop 13 110

thereon to receive a stringer 14 that is threaded through the loops and has its free ends secured together by a suitable lock 15. The towels with this form of loop will be 5 mounted in substantially the same manner as described and be delivered and collected by the laundry in bundles of suitable size for the cabinet in which they are used.

I claim as my invention:

- 10 1. A towel support having a surface whereon the clean towels are placed in a bundle, one upon the other, each towel having a comparatively long tape formed in a loop thereon, said tapes being bunched together when the towels are assembled in a bundle, a ring threaded through said loops for holding the towels against accidental separation, the ends of said ring being secured together for transport with the clean 15 towels from the laundry to the support and for transport with the soiled towels from the support to the laundry, said tapes permitting freedom of use of each towel and its entire wiping surface.
- 20 2. A towel support having a surface whereon the clean towels are placed in a bundle, one upon the other, each towel having a comparatively long tape formed in a loop thereon, said tapes being bunched together when the towels are assembled in a bundle, flexible means threaded through said loops for holding the towels against accidental separation, the ends of said flexible means being secured together for transport 25 with the clean towels from the laundry to the support and for transport with the soiled towels from the support to the laundry, said tapes permitting freedom of use of each towel and its entire wiping surface.
- 30 3. A towel cabinet having a shelf therein

whereon the clean towels are placed in a bundle, one upon the other, said cabinet having a space beneath said shelf forming a soiled towel receptacle, each towel having a comparatively long tape thereon to 45 depend below said shelf when the towels are laid thereon, a ring-like means for stringing said tapes together for holding them against accidental separation and for transport with the clean towels from the laundry 50 to the cabinet and, for transport with the soiled towels from the cabinet to the laundry, said tapes allowing each towel to be removed from the shelf and held in front of the cabinet with freedom of use of the entire wiping surface of the towel.

4. A towel cabinet having a shelf in the upper portion thereof whereon a bundle of clean towels placed one upon another is laid, said shelf having an upwardly projecting 60 ledge and a recess in its edge between said ledge and the wall of the cabinet, each of said towels having a comparatively long tape with a loop formed therein, said tapes being bunched together when the towels are 65 formed in a bundle, and depending through the recess in said shelf, means whereon said tapes are strung for holding them and said towels together allowing each towel to be lifted and used and dropped into the cabinet 70 beneath said shelf, said means having a locking device for securing its ends together and holding said tapes against separation for transport with the clean towels from the laundry to the cabinet and with the soiled 75 towels from the cabinet to the laundry.

In witness whereof, I have hereunto set my hand this 5th day of March 1918.

GEORGE A. STEINER.
